UNITED STATES PATENT OFFICE.

WILLIAM E. HAXTUN, OF KEWANEE, ILLINOIS, ASSIGNOR TO THE HAXTUN STEAM HEATER COMPANY, OF SAME PLACE.

DRAFT-REGULATOR.

SPECIFICATION forming part of Letters Patent No. 411,768, dated September 24, 1889.

Application filed March 8, 1889. Serial No. 302,551. (No model.)

To all whom it may concern:

Be it known that I, WILLIAM E. HAXTUN, residing at Kewanee, in the county of Henry and State of Illinois, and a citizen of the United States, have invented a new and useful Improvement in Draft-Regulators, of which the following is a specification, reference being had to the accompanying drawings, in which—

10 Figure 1 is a plan view. Fig. 2 is a front elevation. Fig. 3 is a plan view showing another arrangement of the devices. Fig. 4 is a detail.

15 This invention relates to automatic draft-regulators, and is primarily designed for use in connection with hot-water heating apparatus for buildings, but may be used with steam-heating apparatus.

20 The object of my invention is to construct a draft-regulator for controlling the dampers of the furnace, which shall be operated by the variation in the temperature of a circulating-pipe, through which hot water or steam flows from a boiler. This I accomplish as illustrated in the drawings, and hereinafter described.

25 That which I claim as new will be pointed out in the claim.

30 In the drawings, A represents the masonry of the furnace.

B is a hot-water or steam boiler set in the masonry.

35 C are circulating-pipes leading from the boiler B. One of these circulating-pipes at some distance from the boiler B is firmly secured at some convenient point to a solid timber D of the building by clamps d d, or by other suitable means, so that the pipe at that point is held perfectly stationary.

40 E is a freely-swinging lever, which is pivoted at one end on a pivot f, secured to one of the timbers F of the building by iron plates or otherwise. This lever E, near the pivot f, is pivoted on a pivot c, which, as shown in Figs. 1 and 2, is firmly secured on the circulating-pipe C. When it is not convenient to attach the pivot c to the pipe C, as shown in Figs. 1 and 2, it may be secured, as shown in Fig. 3, by means of a forked plug, (see Fig. 4,) 45 which is secured in one end of a T-coupling.

The pivot c and the lever E are to be located

55 at a convenient distance from the clamps d—say twenty or thirty feet or more. The outer end of the lever E is supported by means of a chain e in such manner that it can swing horizontally freely.

60 G is a chain or cord connected with the outer end of the long arm of the lever E. This chain G runs over a pulley g, and is connected at its lower end with an arm h, attached to the draft-door H of the furnace, as shown in Fig. 2.

I is a second chain, which is also connected with the outer end of the long arm of the lever E. This chain I passes over a pulley i, 65 and is attached to the check-draft door J in the chimney of the furnace behind the boiler B, as shown in Fig. 2.

K are the return-pipes to the boiler.

70 The variation in the temperature of the hot water or steam passing through the circulating-pipe C causes it to expand or contract longitudinally according as the temperature rises or falls, moving the pivot c away from or toward the stationary point at the clamps d. The expansion of the pipe C moves the lever E toward the furnace, allowing the draft-door H to close and opening the check-draft door J. The contraction of the pipe C moves the lever E away from the furnace, opening the draft-door H and allowing the check-draft door J to close. By adjusting the lever E and the lengths of the chains G and I the expansion and contraction of the circulating-pipe can be 80 made to operate the doors, so as to regulate the temperature of the entire heating apparatus automatically. The length of the lever used will depend upon the distance of the pivot c from the stationary point at the clamps d, as the greater the distance the greater will 85 be the movement of the pivot c and the lever E. 90

The doors H and J are to be so arranged that they can close by gravity.

95 The pipe C may be any one of the circulating-pipes, or when the main circulating-pipes already in the building are not well adapted for the purpose a secondary pipe may be put in, provided at a proper distance from the boiler with a T-coupling and an air-valve and a separate return-pipe.

100 Branch pipes may be attached to the pipe C at desired points between d and F, provided

they are so attached as not to interfere with the movement of the pipe C.

The lever E may be a simple lever, as shown, or, if necessary, it may be a compound lever.

5 The pivots e and f must fit closely, so that there will be no lost motion at those points.

Instead of securing the circulating-pipe C at the point D and allowing it to expand toward the boiler, it is evident that the fixed 10 point may be at L, the expansion then being toward D, which should then be free, the position of the lever and the arrangement of the chains being changed accordingly.

Various automatic devices have been used 15 for regulating dampers and valves by the expansion and contraction of different parts of furnaces, stoves, and radiators, or of tubes or bars connected therewith; but I am not aware that heretofore a valve or damper has been 20 controlled by the expansion and contraction of a steam or hot-water circulating pipe held

stationary at some point, and a lever pivoted to said circulating-pipe at a distance from the stationary point and connected with a draft-door.

25

What I claim as new, and desire to secure by Letters Patent, is—

The combination, with a furnace, a boiler, and a hot-water or steam circulating pipe held stationary at some point, but free to expand 30 and contract with variations in temperature of the hot water or steam that flows through said pipe from the boiler, of a freely-swinging lever pivoted directly to said circulating-pipe at a distance from its fixed point, and a connection between said lever and a draft-door of the furnace, substantially as described. 35

WILLIAM E. HAXTUN.
